(57) **CLAIM**

The ornamental design for a two handed baseball batting training device, as shown and described.

DESCRIPTION

FIG. 1 is an isometric view of my two handed baseball batting training device showing my new design.

FIG. 2 is a front elevational view thereof, the rear view being identical;

FIG. 3 is a right side elevational view thereof, the left side being identical;

FIG. 4 is a top plan view thereof;

FIG. 5 is a bottom plan view thereof;

FIG. 6 is a perspective view of a second embodiment of FIG. 1; and,

FIG. 7 is a perspective view of a third embodiment of FIG. 1.
